Meredith & Keyhani, PLLC

(57) **CLAIM**

The ornamental design for a flexible pendant, as shown and described.

DESCRIPTION

FIG. 1 is a front and left perspective view of a flexible pendant showing my new design;

FIG. 2 is a front and left side perspective view thereof shown in a flexed condition;

FIG. 3 is a front elevational view thereof;

FIG. 4 is a front elevational view thereof shown in a flexed condition;

FIG. 5 is a rear elevational view thereof;

FIG. 6 is a rear elevational view thereof shown in a flexed condition;

FIG. 7 is a left side elevational view thereof;

FIG. 8 is a left side elevational view thereof shown in a flexed condition;

FIG. 9 is a top plan view thereof;

FIG. 10 is a top plan view thereof shown in a flexed condition;

FIG. 11 is a bottom plan thereof;

FIG. 12 is a bottom plan view thereof shown in a flexed condition;

FIG. 13 is front and left side perspective view thereof; and,

FIG. 14 is a front and left side perspective view thereof shown in a flexible condition.

The broken lines shown in the figures represent environment and form no part of the claimed design.

1 Claim, 4 Drawing Sheets
